MEDALLION HOUSING FOR AN AUTOMOBILE HOOD

Henry T. King and Edwin S. Getner, Detroit, Mich., assignors to Chrysler Corporation, Highland Park, Mich., a corporation of Delaware

Application July 22, 1954, Serial No. 31,538

Term of patent 7 years

(Cl. D14—18)

Fig. 1 is a front elevational view of a medallion housing for an automobile hood showing our new design;

Fig. 2 is a top plan view thereof;

Fig. 3 is a side elevational view thereof; and

Figs. 4, 5 and 6 are sectional views taken on the lines 4—4, 5—5 and 6—6 respectively of Fig. 1.

We claim:

The ornamental design for a medallion housing for an automobile hood, substantially as shown and described.
